Patented Aug. 6, 1963

195,884

FLIGHT CONTROLLER PANEL

Robert E. Clark, Minneapolis, and Earl R. Stensgaard, Stillwater, Minn., assignors to Minneapolis-Honeywell Regulator Company, Minneapolis, Minn., a corporation of Delaware

Filed Aug. 8, 1961, Ser. No. 66,259

Term of patent 14 years

(Cl. D52—6)

FIG. 2

FIG. 1

FIGURE 1 is a front view of a flight controller panel embodying our new design;

FIGURE 2 is a side view thereof; and

FIGURE 3 is a vertical sectional view, on an enlarged scale, of a rocker button portion of our design.

The essential features of the design reside in the portions shown in full lines.

We claim:

The ornamental design for a flight controller panel, substantially as shown and described.
